UNITED STATES PATENT OFFICE.

JULES H. VENON, OF NEW YORK, N. Y.

DESIGN FOR A GOBLET OR SIMILAR ARTICLE OF TABLE GLASSWARE.

Application filed November 6, 1928. Serial No. 28,782. Term of patent 7 years.

To all whom it may concern:

Be it known that I, JULES H. VENON, a citizen of the United States and resident of the city, county, and State of New York, have invented a new, original, and ornamental Design for a Goblet or Similar Article of Table Glassware, of which the following is a specification, reference being had to the accompanying drawing forming part thereof.

In the drawing are shown, in Figs. 1 and 2, side views taken at right angles to each other

of a goblet embodying my new design; Fig. 3 is a section of the stem, taken on the line 3—3 of Fig. 1.

The important feature of the design is the outline or shape of the stem portion of the article.

I claim:

The ornamental design for a goblet or similar article of table glassware, as shown and described.

JULES H. VENON.
